UNITED STATES PATENT OFFICE.

ROBERT B. HANSELL, OF BALTIMORE, MARYLAND.

DESIGN FOR A PLATE.

SPECIFICATION forming part of Design No. 24,410, dated June 18, 1895.

Application filed April 2, 1895. Serial No. 544,213. Term of patent 14 years.

To all whom it may concern:

Be it known that I, ROBERT B. HANSELL, a subject of the Queen of Great Britain, residing in the city of Baltimore, State of Maryland, have invented and produced a new and original Design for a Plate, of which the following is a specification, reference being had to the accompanying drawings.

In the drawings, Figure 1 is a plan view of the plate or a section thereof, and Fig. 2 is a side elevation of the same.

The leading feature of my design consists in the surface configuration of the plate, which presents a plain surface of a sinuous shape, the edges of the plate on alternate sides being

made hollowing, which thus forms the sinuous shape of the upper surface.

A represents the plate proper, B the sinuous upper surface and C the hollowing edges which are diagonally opposite each other on alternate sides of the plate.

What I claim is—

The design for a plate herein shown and described.

In testimony whereof I affix my signature in presence of two witnesses.

ROBERT B. HANSELL.

Witnesses:

FELIX R. SULLIVAN,
G. DAVIS MEANITT.
